[57] CLAIM

The ornamental design for a “dispensing cap,” as shown and described.

DESCRIPTION

FIG. 1 is a front elevation view of a dispensing cap in accordance with my new design;

FIG. 2 is a top plan view thereof;

FIG. 3 is a left side elevation thereof, the right side view being a mirror image thereof, except for differences in the threading;

FIG. 4 is a rear elevation view thereof;

FIG. 5 is a bottom plan view thereof;

FIG. 6 is a perspective view thereof; and,

FIG. 7 is a perspective view similar to FIG. 6 but with the lid portion of the cap in an open position.
